FIG. 1 is a front elevational view of a merchandise display package embodying my design; the front panels on the individual compartments being each die-cut as shown in dotted outline and by the horizontal line thereon so that the compartment can be broken into;

FIGS. 2 and 3 are opposite side elevational views of said package;

FIGS. 4 and 5 are opposite plan views of said package;

FIGS. 6 and 7 are, respectively, vertical and horizontal sectional views of said package taken on the lines 6-6 and 7-7 of FIG. 1; and

FIG. 8 is a fragmentary sectional view of one of said compartments shown broken into with the front panel thereof separated at said horizontal die-cut line and partly torn along the other die-cut lines for access to merchandise packaged in said compartment; a sample article of merchandise being shown for illustrative purposes in dotted outline in this FIG. 8.

The essential features of my design reside in the portions shown in full lines.

I claim:

The ornamental design for a merchandise display package, as shown and described.
